(57) **CLAIM**

I claim the ornamental design for a horizontal wall mount rack, as shown and described.

DESCRIPTION

FIG. 1 is a front isometric view of a horizontal wall mount rack according to my design shown in use;

FIG. 2 is a front isometric view of the horizontal wall mount rack shown in another state of use;

FIG. 3 is a rear isometric view of the horizontal wall mount rack shown in FIG. 1;

FIG. 4 is a rear isometric view of the horizontal wall mount rack shown in FIG. 2;

FIG. 5 is a front elevation view thereof;

FIG. 6 is rear elevation view thereof;

FIG. 7 is a top plan view thereof, the bottom plan view being a mirror image; and,

FIG. 8 is a side elevation view thereof, the opposite side elevation view being a mirror image.

The broken lines shown represent unclaimed panels and portions of the horizontal wall mount rack, all of which form no part of the claimed design.
